PACKAGING TAPE OR THE LIKE
Matthew B. Blish, Box 151, Oak Park, Ill.
Filed Nov. 1, 1962, Ser. No. 234,790
4 Claims. (Cl. 229—49)

This invention relates to packaging and more particularly to tape therefor.

The main object of the invention is to provide a packaging tape of highly decorative character for the adornment of gift wrappings.

Another object is to provide an inexpensive means for imparting additional elegance to fancy merchandising packaging such as food specialties, cosmetics, confections, jewelry, and other commodities which rely upon attractive ornamental packaging for sales promotions.

A further object of the present invention is to provide a tape for binding packages and at the same time provide a construction which lends itself to labeling in a novel manner, thereby achieving two distinct advantageous results in a single construction.

A still further object is to provide a package binding tape which permits its seal to be quickly and easily broken for opening tape sealed packages.

Other objects and advantages of the invention will be apparent from the following detailed description taken in connection with the accompanying drawings which form a part thereof.

In the drawings:

FIG. 1 is a central vertical sectional view of the tape in its normally longitudinal compact form.

FIG. 2 is a rear face plan view of the tape as shown in FIG. 1.

FIG. 3 is a completely open rear face plan view of one form of the tape prior to folding.

FIG. 5 is a central vertical sectional view illustrating a modified form of the tape shown in FIG. 4 and in a

FIG. 6 is a fragmentary perspective view of one form

FIG. 7 is a fragmentary perspective view of a modified

Referring to the drawings, the tape shown in FIG. 1 is integrally formed of longitudinally flexible material and may be of 27-lb. paper stock such as flatback or crane

may be of 27 lb. paper stock such as flatback or crepe. The two outer longitudinal base portions 10 and 10a are coated on the rear face side with an adhesive 11 and 11a as shown in FIGS. 2 and 3. Pressure-sensitive adhesive or water-activated glue may be used.

The adhesive coated base portions are formed or folded outward at the longitudinal fold lines, 12 and 12a, and the adhesive free intermediate portions 13 and 13a are formed or folded inward at the longitudinal fold lines 14 and 14a providing an adhesive free central portion 15. In use, the longitudinal base portions 10 and 10a are adhesively bonded to the surface of a package leaving the adhesive free intermediate portions 13 and 13a and the adhesive free central portion 15 horizontally raised above the package surface producing an unusually novel decorative effect for packaging tape.

FIG. 4 shows a form of the tape construction produced from longitudinally flexible material having sufficient cross section rigidity to withstand against longitudinal fold lines, without remaining foldably collapsed when unspooled. As shown in FIG. 4, the tape releases tension from its coiled and collapsed position upon unspooling and the extent of release is dependent upon the degree of resiliency of the material selected. The longitudinal base portions 10b and 10c are adhesively coated similarly to the longi-

2

tudinal base portions 10 and 10a in FIG. 2. Upon adhesively bonding the tape to a package surface, the adhesive free intermediate portions 13b and 13c provide springing action horizontally elevating the adhesive free central portion 15a sufficiently above the package surface to produce a highly ornamental third-dimensional effect for a packaging tape as shown in FIG. 6.

FIG. 5 shows a modified form of the tape shown in FIG. 4. After adhesively applying the tape to a package, 10 the adhesive free central portion 15a may be perked up and thereby elevated to a still further degree by sliding the fingers along its length while grasping its side edges between the fingers. This novel decorative effect is provided by the centered fold line, indicated at 16 in FIGS. 15 5 and 7, and indicated at 16 as optional in FIG. 3.

Unusual and highly decorative packagings may be attained by employing variously colored designs or indicia upon the adhesive free central portion in contrast to colors of the longitudinal base portion, thereby imparting an unique dual taped appearance, whereby the body of the adhesive free central portion appears to be separately formed when the tape is adhesively applied to a package surface. Contrasting colors indicated on the longitudinal base portions at 17 and 17a in FIG. 6 and at 17b and 17c in FIG. 7, and designs indicated at 18 in FIG. 6 and at 18a in FIG. 7 are examples of but some of the many colors and designs which may be used. The contrasts may be effectively provided for point-of-sale advertising, labeling, product identification, seasonal sales appeal combined with special designs, premium deals and the like.

The added convenience for quickly and easily breaking the seal for opening tape sealed packages is provided by grasping the elevated adhesive free central portion with the fingers and pulling the tape free of the package.

35 Various other arrangements may be produced without departing from the scope of the invention and the tape is not limited to packaging applications, but may be employed for various decorating and sealing uses. It is to
40 be understood that all matter contained in the foregoing descriptions or shown in the accompanying drawings shall be interpreted as illustrative and not in a limiting sense; that the tape may be of folded stock or otherwise formed, such as by molding or extruding, for example; that certain changes from the exact shapes or constructions shown,
45 or materials described, and fully comprehended by the spirit of the invention may be made without affecting the scope and spirit of the invention as hereinafter claimed.

What is claimed is:

1. A longitudinally flexible tape or the like comprising an integrally formed portion disposed longitudinally of the tape defining a first base portion, said first base portion having an outer side edge forming a peripheral side edge of the tape and an opposing inner side edge disposed contiguous to a first fold line formed parallel of said inner side edge, an integrally formed portion disposed longitudinally of the tape defining a second base portion having an outer side edge forming an opposing peripheral side edge of the tape and an opposing inner side edge contiguous to a second fold line formed parallel of said inner side edge, each of the base portions having an adhesive coating extended lengthwise of the tape on one face side defining a base portion rear face side opposing a front face side of each base portion, a portion formed longitudinally of the tape and parallel of the first base portion having an inner side edge contiguous to said first fold line and an opposing outer side edge contiguous to a third fold line defining a first intermediate portion disposed foldably overlying the front face side of said first base portion, a portion formed longitudinally of the tape and parallel of the second base portion having an inner side edge contiguous to said second fold line and an opposing

outer side edge contiguous to a fourth fold line defining a second intermediate portion disposed foldably overlying the front face side of said second base portion, a portion formed longitudinally of the tape having one side edge contiguous to said third fold line and an opposing side edge contiguous to said fourth fold line defining a central portion disposed foldably overlying the intermediate portions, whereby upon bonding the rear face sides of the base portions juxtaposed to a plane surface the outer side edges of the intermediate portions are secured above the horizontal plane of the base portions thereby raising the central portion above the intermediate portions and facilitating elevating movability of the central portion.

2. The invention as defined in claim 1, in which the central portion is provided a top plane surface disposed normally flat and substantially parallel of the first and second base portions and disposed horizontal of said first and second base portions upon foldably disposing the first intermediate portion overlying the first base portion and foldably disposing the second intermediate portion overlying the second base portion.

3. The invention as defined in claim 1, in which the central portion is provided a longitudinal fold line disposed substantially central of the transverse section of said central portion and extended lengthwise of the tape.

4. The invention as defined in claim 1, in which the

transverse section of the first base portion is of greater width than the transverse section of the first intermediate portion providing a longitudinal margin of said first base portion extended horizontally outward beyond the outer edge of said first intermediate portion and disposed lengthwise of the tape upon foldably disposing the first intermediate portion overlying the first base portion, and the transverse section of the second base portion is of greater width than the transverse section of the second intermediate portion providing a longitudinal margin of said second base portion extended horizontally outward beyond the outer edge of said second intermediate portion and disposed lengthwise of the tape upon foldably disposing the second intermediate portion overlying the second base portion.
